BUCKLE

Howard Beazley, Marshall, Mo.

Application December 2, 1940, Serial No. 368,166

6 Claims. (Cl. 24—173)

My invention relates to a buckle and more particularly to a buckle for use with a safety belt such as worn by airplane pilots or parachutists. Such belts are subject to great strain when in use and to be effective must be provided with fastening means which will withstand strains without being released thereby but which may be quickly released when necessary with the minimum of exertion.

The object of my invention is to provide a buckle of simple and rugged construction which will meet the requirements of such service. To this end I provide a buckle comprising a frame attached at one end to the fixed end of a belt and provided at the other end with a keeper for the free end of the belt, the free end of the belt being engaged by a tongue, or preferably a gang of tongues, the action of which is controlled by an independently movable finger piece.

In the accompanying drawing, which illustrates one form of buckle made in accordance with my invention together with a belt to which it is applied, Figure 1 is a top plan view showing the buckle in locked position; Figure 2 is a similar view showing the buckle in released position; Figure 3 is a bottom plan view; Figure 4 is a section taken on the line 4—4 of Figure 1; Figure 5 is a section taken on the line 5—5 of Figure 2, the belt being omitted; and Figure 6 is a side elevation of the buckle alone.

The frame 1 of my buckle, which is preferably formed of a casting, is provided at one end with a plate 2 to which the fixed end 3 of the belt is secured by any suitable means, such as rivets 4. At the opposite end the frame is provided with a keeper 5 for the free end 3' of the belt. Formed in the lower face of the frame are pockets 6, preferably three in number. Positioned in each pocket is an arm 6' mounted on a cross shaft 7. Each arm carries a tongue 8 which projects upwardly through a slot 9 in the upper face of the frame. The lower edge of each arm is provided with a cam face 10 for cooperation with the tongue controlling means hereinafter described.

Extending through the frame parallel with the shaft 7 is the actuating bar 11 which is formed with three transverse slots to provide cam faces 12. Formed on the ends of the bar 11 are short non-circular sections 13 which engage with correspondingly shaped openings in arms 14. The ends of arms 14 are connected by a finger piece 15 in the form of a plate having an edge which is turned upwardly when the buckle is in locked position, as best shown in

Figure 4. The arms and finger piece may be formed integral but for convenience in assembling the device I prefer to make one or both detachable by means of screws 16 passing through lugs 17 on the arm into the plate 15. The free end 3' of the belt is provided with a row of grommets 18 spaced to register with tongues 8. While only one row of grommets is essential, I prefer to use two or more rows, as shown in Figure 1, to provide adjustability for the belt.

In using my buckle when it is desired to secure the belt, the finger piece is swung into the position shown in Figure 5. This rotates the bar 11 into such position that the tongues fall down against the cam faces 12. The free end of the belt is passed under the keeper 5 and over the body of the frame until the desired row of grommets registers with the tongues.

20 The finger piece is now swung into the position shown in Figure 4. This rotates the bar 11 causing the cam faces 12 to raise the tongues into vertical position. The cam face 10 of the arm now bears against the curved surface of the bar. 25 In this position the pull of the belt on the tongues has no tendency to rotate the bar and hence the buckle cannot be released by excessive strain on the belt. To release the buckle the finger piece is grasped and swung upwardly. As soon as the cylindrical portion of the bar moves out of engagement with cam faces 10 of the arms of 6', the pull of the belt on the tongues completes the releasing movement automatically by the pressure of faces 10 against the edges of faces 30 12. The cam faces 12 should be so positioned that the releasing movement will begin when the arms 14 are at substantially right angles to the frame.

Having fully described my invention, what I claim as new and desire to secure by Letters Patent of the United States is:

1. In a device of the class described, a frame attached at one end to the fixed end of a belt, said frame being provided at the other end with a keeper for the free end of the belt, a tongue movably carried by the frame and projecting through a face thereof to engage the free end of the belt, and a pivotal finger piece movable independently of the tongue but controlling the action of the latter.
2. In a device of the class described, a frame attached at one end to the fixed end of a belt, said frame being provided at the other end with a keeper for the free end of the belt, a pivotal tongue movably carried by the frame and pro-

jecting through a face thereof to engage the free end of the belt, a pivotal finger piece, and a cam carried by the frame and moved by the finger piece for actuating the tongue.

3. In a device of the class described, a frame attached at one end to the fixed end of a belt, said frame being provided at the other end with a keeper for the free end of the belt, a cross shaft mounted in the frame, an arm mounted on the shaft and carrying the tongue, an actuating bar having a cam controlling the movement of the tongue, and a finger piece for rotating the actuating bar.

4. In a device of the class described, a frame attached at one end to the fixed end of a belt, said frame being provided at the other end with a keeper for the free end of the belt, a pocket in the lower face of said frame and communicating through a slot with the upper face thereof, an arm pivotally mounted in said slot and provided with a tongue extending through the slot, an actuating bar for controlling the movement of the tongue, and a pivotal finger piece for rotating the bar.

5. In a device of the class described, a frame attached at one end to the fixed end of a belt, said frame being provided at the other end with a keeper for the free end of the belt, said frame including an intermediate perforate portion forming a support for the free end of the belt, a tongue carried by the frame and projecting through said intermediate perforate portion to engage the free end of the belt, and a finger piece carried by the frame and pivoted thereto at a fixed point, said finger piece controlling the engagement of the tongue with the strap, said finger piece forming when in closed position a releasable belt guard at the end of the frame to which the belt is attached.

6. In a device of the class described, a frame attached at one end to the fixed end of a belt, a tongue carried by said frame and movable relatively thereto to engage and disengage the free end of the belt, and a member movable relatively to the frame, said member operating to release the tongue from the belt while the former is under the load strain of the latter.

HOWARD BEAZLEY.
